Spur Middleton Donaldson & Hall

ATTORNEYS.

UNITED STATES PATENT OFFICE

JOHN FRANCIS BABBITT, OF LOUISVILLE, KENTUCKY, ASSIGNOR TO JOHN V. PILCHER,
OF LOUISVILLE, KENTUCKY

VANITY CASE

Application filed June 29, 1929. Serial No. 374,887.

My said invention relates to improvements in vanity cases of the type serving as a container for powder in loose form as distinguished from a cake or compact.

5 The invention aims to provide a case in which the powder will be effectually prevented from escaping from the powder compartment while the article is being carried about the person and when not in use, but 10 wherein the pad or applicator will always be in readiness for use on opening the case.

The invention further aims to provide a construction which will be very economical of manufacture, of attractive appearance, 15 and durable in use.

With these several objects in view, the invention includes the novel construction hereinafter described and defined by the appended claims.

20 My improved vanity case is illustrated in the accompanying drawings in which:

Figure 1 is a plan view with the sections opened out.

Fig. 2 is a central longitudinal vertical 25 section through the same.

Fig. 3 is a similar section with the case sections closed together, and

Fig. 4 is a side elevation.

Referring by reference characters to these 30 drawings, the vanity is shown as comprising a powder containing section 1 and a cover section 2. These are shown in the present drawings as circular, the lower section having an inwardly displaced or offset annular edge portion 1^a which telescopes within the cylindrical wall of the cover section to make a tight closure.

The two sections are hinged together by 40 means of a hinge 3, the leaves of which are made of sheet metal and provided with tongues 3^a and 3^b which are inserted through slots in the walls of the body and cover sections.

The body section is provided with a catch 45 carried by a spring wire 5 and serving to engage the cover to hold the same releasably in closed position, such catch forming the subject matter of an application filed by me in the United States Patent Office on the 1st day of June, 1929, Serial Number 367,727.

The powder is contained in a pan 6, the vertical wall of which is of slightly less diameter than the case section 1, leaving an annular space to receive the spring 5, and having an outwardly extended or horizontal peripheral flange 6^a designed to snugly fit within the case section. 55

The powder pan 6 is provided with a closure member 7 which has a downwardly projected annular flange 7^a designed to telescope within the annular wall of the pan 6 with a snug fit creating sufficient friction to hold it normally in position, and the upper surface of this closure member 7 is preferably made slightly convex and provided with an exit opening (or openings), for the powder. Preferably, I use but a single relatively large opening arranged centrally of the closure member, so that when the pad 8 is held in position over the opening and the device 60 agitated a sufficient quantity of the powder 65 for use will be projected through the opening onto the under side of the pad. 70

I provide means for pressing the pad tightly against the closure member when the cover 75 section is closed whereby escape of powder is prevented, such means taking the form of a spring pressed disk and preferably, I make this disk in the form of a mirror, whereby it serves a two fold purpose. 80

Such mirror is indicated in the drawing at 9 and it is retained in the cover section by a bezel 10 having a peripheral flange 10^a which is retained in position by the hinge tongues 3^a and also the projections 2^b stuck or punched 85 inwardly from the annular wall of the cover section.

A spring 11, preferably of leaf form, lying between the mirror and back of the cover section tends normally to press the mirror (and 90 bezel), outward against the retaining means referred to, but permits it to yield under pressure.

These mirrors are usually made of glass and to prevent danger of breakage, I interpose a metal plate or disk 12 between the mirror and spring, but obviously, if desired, the mirror could be made of polished metal or unbreakable material and the backing plate dispensed with. 95 100

When the sections are closed together, it will be observed that the mirror will cause the pad to be pressed tightly against the edge of the opening in the closure member or top of the powder container and will effectually prevent the escape of any powder from the pan around or past the pad, the seal being rendered the more effective by reason of the convexity of the pan closure member, and also by the fact that the central portion of the pad will be caused by the pressure to project somewhat into the opening.

When the vanity case thus closed is carried around, as in a hand bag, the portion of the pad exposed through the opening will receive enough adherent powder to be ready for application to the face of the user.

Having thus described my invention, what I claim is:

- 20 1. A vanity case comprising a pair of hinged sections, a powder pan carried in one section having a closure member provided with a powder exit opening, an applicator pad overlying said closure member and the opening therein, and yielding means carried by the other section for pressing the pad against the pan closure member when the sections are closed.
- 25 2. A vanity case according to claim 1 in which the yielding pressing means comprises a disk member movably retained in its section, and a spring interposed between the disk and back of said section.
- 30 3. A vanity case according to claim 1 in which the pad pressing means comprises a mirror yieldably mounted in the cover section.
- 35 4. A vanity case according to claim 1 in which the pan closure member is of convex form and provided with a central aperture.

In testimony whereof, I affix my signature.
JOHN FRANCIS BABBITT.
